William P. Sample
Gales Patent

The Schedule referred to in the Gales Patent and making part of the same concerning a description in the words of the said William P. Sample himself of his improvement in the machine for cultivating cotton called Sample's improved cotton scraper and Harrow.

To all to whom these presents shall come. Be it known that; William P. Sample of the County of Bedford and State of Virginia have invented a new and useful improvement in the cultivation of cotton which shall be called Sample's improved cotton scraper & Harrow and that the following is a full & exact description of the construction & operation of said machine as invented & improved by me. A. represents the longest wooden beam about five feet long and from 2 $\frac{1}{2}$ to 3 $\frac{1}{2}$ inches square. B. represents the short wooden beam about four feet long and of the same size as A. These beams may be longer or shorter or larger or smaller according to the fancy of the builder & the kind of soil in which they are to be used. C. the wooden tube about 8 inches long of a triangular form which is let into the hind end of the short beam with an oblique tenon in order that the scathers or harrows attached to this tube may move nearly (but not quite) on a right line with the beam. D. represents the iron plates or scrapers from twelve to twenty inches long, as the soil may consist of from five to eight inches wide. There are several otherwise fastened on each side of the tube C. leaving a space in front of about four inches widening behind according to the soil. The fancy of the cultivator. & length of the scrapers from fifteen to twenty five or thirty inches, a dry sandy soil admitting the use of long scrapers & a close gravelly soil the short kind. These scrapers pass on each side of the cotton & therefore clean an entire row at once & hollow being left in the lower end of tube C. of four inches in front, four or six inches in the back part & four or five inches deep, will permit the machine to run immediately on the cotton without injury to scrapers or harrows on both sides at the same time. To make the scrapers cut & shave the earth "grap" wholly.

Sept 3, 1831

nearly the lower part would be sharp'd from one to two inches of at least forward. Likewise about one half inch of the front part would be bent so as to run on a straight line with the cotton to prevent it from other tools from injuring it. C represents the foot on which the long beam rests & may be about 12 or 14 inches long. D represents the upright on which the handles are fastened by a pin passing through the uprights & handles by which the machine is governed. E represents the point where the two beams are mortised or pinned together. F represents the brace or pin let into the beams at A & B near the hind end in order to keep them steady & firm & about 18 inches apart. G represents the handles. To convert the same frame or machine into a cotton harrow take off the scraper & insert into the foot of the same below the front iron teeth or small coulters about six inches apart these teeth or coulters are to be used to run on each side of the cotton & are designed to break up the ground. If left in among the cotton a sufficient quantity of mould to cover young of rattle bird if it should be desired to use a complete harrow with two three or more teeth on each side take off the below & attach this harrow in place of the scraper & it will work on the same principle. I have accost that many cotton scrapers & harrows are in use & some of them so far as a single scraper is like a double scraper resemble mine. (That is the iron or steel plate separates from the machine.) Likewise I have seen harrows to not on both sides of the cotton at the same time, but in every such case the horse or mule was compelled to walk inmediately on the cotton. Therefore the claim I make for a patent on my invention does not rest on the form of the plates of the scraper nor on the form of the iron teeth of the harrow separated from the machine, but mainly upon the wooden part; for by the mechanism & form of the wooden part of my machine the horse or mule walks one foot from the cotton, when at the same time the instrument is directly on it. The scraper being fixed on the same below double work is done by the machine and more steadily. And in this way the same effect is produced on the same principle. Note. Although the mechanism of the wooden part is the same in improvement - yet the application of scrapers & harrows both

to make a machine being a new principle, at least so far as to do double work, I presume that the whole ought to be embraced in the patent
